UNITED STATES PATENT OFFICE.

HAROLD G. DAVIS, OF DENVER, COLORADO.

DESIGN FOR AN OIL-DISPENSING CASING.

Application filed July 13, 1925. Serial No. 14,070. Term of patent 14 years.

To all whom it may concern:

Be it known that I, HAROLD G. DAVIS, a citizen of the United States, residing at the city and county of Denver and State of Colorado, have invented a new, original, and ornamental Design for Oil-Dispensing Casing, of which the following is specification, reference being had to the accompanying drawing, forming a part thereof.

The figure is a perspective view of an oil dispensing casing showing my new design.

I claim:

The ornamental design for an oil dispensing casing, as shown.

In testimony whereof I affix my signature.

HAROLD G. DAVIS
